UNITED STATES PATENT OFFICE.

ALFRED ZIEGLER AND JOHN O. REMINGTON, OF BOSTON, MASSACHUSETTS.

DESIGN FOR A SHADE-PULL.

SPECIFICATION forming part of Design No. 28,188, dated January 18, 1898.

Application filed October 14, 1897. Serial No. 655,226. Term of patent 31 years.

To all whom it may concern:

Be it known that we, ALFRED ZIEGLER and JOHN O. REMINGTON, of Boston, county of Suffolk, and State of Massachusetts, have invented and produced a new and original Design for Shade-Pulls, of which the following is a specification, reference being had to the accompanying drawing, forming a part thereof.

The drawing shows an elevation of our newly-designed shade-pull.

As shown in the drawing, the leading or characteristic features of our design comprise the unitary article shown; and the design consists in a shade-pull comprising a cord *b* and a ball-shaped pendant *a* at the lower end thereof, having on its outer surface undulat-

ing triple-ribbed portions alternately raised and sunken, so as to pass over and under each other and form a knot, as shown in the drawing.

We claim—

The design for a shade-pull as herein shown and described.

In testimony whereof we have signed our names to this specification in the presence of 25 two subscribing witnesses.

ALFRED ZIEGLER.
JOHN O. REMINGTON.
